UNITED STATES PATENT OFFICE.

VOLNEY ERVIN, OF SALT LAKE CITY, UTAH.

PUMP.

1,199,679.

Specification of Letters Patent. Patented Sept. 26, 1916.

Application filed July 10, 1915. Serial No. 39,086.

To all whom it may concern:

Be it known that I, VOLNEY ERVIN, a citizen of the United States, residing at Salt Lake City, in the county of Salt Lake and State of Utah, have invented certain new and useful Improvements in Pumps, of which the following is a specification.

This invention relates to pumps, and more particularly to that class of such devices adapted to be operated by any suitable motive power, and has for its primary object the construction of an improved pump of the oscillating piston type.

A further object of this invention is the provision of a device of the character set forth which shall be economical and efficient of operation, producing a maximum amount of work with a minimum outlay of power.

A still further object of this invention is to provide a pump of the oscillating piston type, essentially adapted for irrigation purposes, but adaptable to all conditions under which such a device can be effectually utilized.

Other objects will appear hereinafter in the description of the invention which consists in the peculiar combination and arrangement of the various co-operating elements of a pump as described in the following specification, and more particularly set forth in the appended claim.

Referring to the drawings forming a portion of this specification and illustrating the preferred embodiment of the invention, and in which similar reference characters indicate similar parts wherever used:—Figure 1 is a front elevation showing the operating mechanism. Fig. 2 is a vertical longitudinal section taken in a plane parallel to Fig. 1. Fig. 3 is a vertical lateral section on the line 3—3 of Fig. 2. Fig. 4 is a detail section illustrating the intake period. Fig. 5 is a detail section illustrating the exhaust period.

The pump comprises a plurality of suitably formed hollow members 6, connected intermediate their ends at 7, and with the exception of the exhaust member 8, and the intake member 9, are closed at their outer ends 10. Adjacent the point of connection of one of the members 6, with the corresponding member, there is provided a small hanger 11, in which is pivoted a flap valve 12, the purpose of which will be hereinafter explained. The series of members 6 are connected adjacent their outer ends by

means of vertically extending strengthening members 13, suitably secured thereto. The entire device is then mounted upon the axle 14, carried in suitable bearings 15, supported by trunnions 16, which are mounted upon the upper edge 17 of a trough or other suitable receptacle 18, adapted to receive water to be raised to a higher level.

Mounted in any suitable manner upon the side of trough 18, and preferably by means of an extension 19, is an eccentric 20, carrying a pitman 21, which is in turn pivotally connected at 22, to the lower of said members 6. The eccentric 20 is driven from any suitable source of power and serves by means of the pitman 21, to carry the entire device upon the axle 14.

The operation of the device is as follows:—The device is placed in such a position that the lower member 9 of the member 6, extends below the surface of the water which it is desired to raise to a higher level, and the device is then rocked to the axle 14, by the means described herein with the following result.

Upon a movement of the device toward the right, as shown in the drawings, an amount of water is scooped up by the lower member 9, and runs down into the end 23 thereof, causing the flap valve 12 to assume the position shown in Fig. 4.

Upon a further revolution of the eccentric which extends to rock the device toward the left, the flap valve 12 of the member 9, closes, thus retaining the water within the member 9.

Upon a second movement toward the right, the operation described for the initial movement will be repeated with the additional operation being such that the water contained within the portion 23 of the member 9 will pass by and open the flap valve 12 of the member 24 in communication with the member 9. This operation is repeated, the water flowing in the direction of the arrows, and the valves 12 opening by means

of the pressure of the water on the under side thereof upon the proper stroke, and closing by means of gravity upon a stroke in the reverse direction. This operation is continued until the water reaches the member 8, from whence it is discharged through the exhaust 26.

It is obvious that the height of the device may be built to conform to the height to which it is desired to raise the water, and that the number of members may be increased at will, the operation being the same.

While I have shown and described the preferred form of my invention, it will be obvious that various changes in the details of construction and in the proportions may be resorted to for successfully carrying my invention into practice, without sacrificing any of the novel features, or departing from the scope of the invention, as defined in the appended claim.

10. What I claim is:—

The combination with a series of inclined members, of a second series of oppositely inclined members in communication therewith at a point intermediate the ends of the first series, a plurality of valves carried by one of said series adapted to form continuous

passages through the communicating members of the other of said series, a plurality of valves carried by said second series adapted to form a plurality of continuous 20 passages with the communicating members of the other series, means for oscillating both of said series of members to cause said valves to open and close in order to govern the length of said passages.

25

In testimony whereof I affix my signature in presence of two witnesses.

VOLNEY ERVIN.
